JUSTIFYING DEVICE FOR PROPORTIONAL SPACING TYPEWRITERS
Pierre Leglise, 23 Rue Pierre Semard, Paris, France
Filed Dec. 18, 1961, Ser. No. 160,050
8 Claims. (Cl. 197—84)

The present invention is directed to a justifying device for typewriters provided with at least two space bars giving two values for the spaces. Although this feature is associated with proportional spacing construction in machines of the present typing art, proportional spacing is not required for the application of the present invention. In the typewriters above referred to, one space bar gives 2-unit spaces, for instance, and the other 3-unit spaces. The availability of two space values makes it possible to carry out justification by substituting one of these values for the other in the number of spaces required for each line, according to the process below:

(1) The operator types a preparatory copy of the text to be justified. A sheet of paper being placed on the platen, the operator draws a vertical line thereon, said line being at the distance from the left hand margin equal to the justified width of typing desired. The preparatory copy is typed with the same space bar used throughout. When justification is to be achieved by line lengthening, the two unit space bar is used throughout the typing of the preparatory copy and no line is permitted to go beyond the vertical line. On the other hand, if justification is to result from contraction of the lines, only the three unit space bar is used and no line is permitted to end before reaching the vertical line.

(2) For sake of clarity, it will be assumed in what follows that justification results from line expansion. Level with each line of the preparatory copy, the operator writes the number of units by which the written line is short with respect to the vertical line. A line short by 5 units is marked 5, a line short by 8 units is marked 8, etc. This analysis of the copy may be carried out by means of a rule graduated in type units; or each line can be completed at the time of typing by a series of dots up to the vertical line, and the counting of these dots will show the deficit of the line considered, taking into account the value of the dot in terms of units.

(3) A line short by n units should obviously be expanded by n units to emerge justified. This will be achieved by actuating the 3-unit space bar instead of the 2-unit one n times, either consecutively or at selected points throughout the line. Generally, because it is the simplest way, the operator counts the first n spaces of the line which are intended for typing with the 3-unit space bar, and marks whatever sign, a cross for instance, at the $(n+1)$ th space, that is, where the 3-unit space bar should be abandoned for the 2-unit space bar. (Instead of counting the first n spaces of the line, the operator may, of course, count the last n ones, or still, n consecutive spaces anywhere in the line; in this case, however, there will be two changes of space bar throughout the line.) Each line of the preparatory copy requires the counting of a number of consecutive spaces specific to said line and the marking of a space the place of which, also, is specific to the line. This operation is time consuming and the frequency of errors increases in proportion to the volume of copy to handle, due to the tedious character of this treatment.

The operations above concern only the preparatory copy. In the course of justification, it is also essential to actuate the space bars in accordance with the marks carried by the preparatory copy; that is in the case of justification through line expansion, the actuation of the 3-unit space bar from the beginning of the line up to and including the space preceding the mark made on the

line, then the 2-unit space bar up to the line end; or, when justification is carried out by line contraction—the preparatory copy having been then typed with the 3-unit space bar—actuation of the 2-unit space bar from the beginning of the line up to and including the space preceding the mark made on the line, then the 3-unit space bar up to the end of the line.

The process above is the quicker of the standard ways, for in case the operator intends to select the n spaces to be modified in each line, the lapses of time respectively required by the marking of the preparatory copy and the carrying out of justification are singularly increased.

In reference to this process, the invention makes possible the saving of much time, both direct saving by elimination of certain operations, and indirect saving through the elimination of the need for careful application on the part of the typist, the steps of the process where errors occur most frequently, being made automatic.

In respect to the preparatory copy, the invention in most cases eliminates, for each line: first, the counting of the number n of consecutive spaces peculiar to the line considered, and next, the marking of the $(n+1)$ th space of said line; or else, the selection and counting of the preferred n spaces and the marking of each of them. On the whole, the preparatory copy no longer requires marking, with the exception of few lines, as will be seen later on. And in the carrying out of justification, the invention relieves the operator of any need to watch marks, as well as effecting constant changes from one space bar to another.

The invention provides these advantages by substituting the actuation of a single member, called master space bar, for the usual direct actuation of the 2-unit and 3-unit space bars, these last bars being made selectively operable by the master space bar.

To this end, the invention includes principally, in combination: a master space bar (which constitutes the only member for introducing the spaces in the course of justification, through its selective control of the subsidiary space bars), an escapement mechanism which each action of the operator on the said master space bar releases, a finger to control the 2-unit and 3-unit subsidiary space bars, said finger moving by a given amount under the action of a return system, dependent on each release of the escapement, and a system for setting the initial position of the control finger in relation to the number of spaces to be modified in each line; the escapement mechanism and the setting system being so arranged that the space bar control finger remains in correspondence with one of the space bars to actuate it only until the number of actions on the master space bar has equalled the number of spaces to which the finger has been set, and then it automatically comes into actuating relationship with the other space bar to actuate only said other space bar up to a new setting operation.

To make automatic justification possible with a device of this kind, it is obviously necessary that each line to be justified comprise a number of spaces at least equal to its number of deficit units (at least equal to the number of excess units in the case of justification by line contraction). A line short by two units should therefore comprise at least two spaces, a line short by ten units, at least ten spaces, and so on. With a justifier expanding the lines, the operator should therefore take care to roughly proportion the maximum permissible deficit to the justification width being used. Thus, only those lines which have deficit amounts likely to be incompatible with the minimum number of spaces normally found in the justification width being used, will require counting as a safety measure. If the operator then ascertains that some of these lines do not permit for automatic justification as aforesaid, they may be treated in the known way,

(e.g. using a combination of 3-unit and 4-unit spaces, the latter being obtained by two consecutive actions on the 2-unit space bar).

One of the objects of the invention is to provide a device for justifying by substituting one space value for another in an adjustable number of spaces, so that the operator need not count a particular number of spaces and mark a sign for the change of space bar on at least one space for the great majority of lines of the preparatory copy.

A further object of this invention is to provide a means whereby the series of spaces, which vary in number from line to line, are typed by actuation of a single master space bar which in turn actuates first one and then, after the preset requisite number of spaces have been typed, the other of the subsidiary space bars. Thus, the operator can type a line in the usual manner, without the necessity of altering his typing technique.

Another object of the invention is the provision of justifying mechanisms which are of simple design and most easy to use.

Another object of the invention is the embodiment of a geared down return system, so that the dynamic properties of the device (travel speed of the moving parts, reactions in the escapement and resistance of the master space bar to operator action) remain practically constant throughout the range of operation.

Another object of the invention consists of providing control of the space bars by a master space bar such that the usual direct actuation of the space bars by the operator is still possible during justification without interfering with the system as hereinbefore described.

A still further object of the invention is to provide a locking system for the justifying device, so that the space bars are entirely cleared when the device is in locked position.

The invention may constitute a part of a typewriter, that is, it may be embodied in the structure of such a typewriter when the typewriter is being built or it may form an accessory intended for attachment to an existing typewriter. The latter form will be now described in reference to the accompanying drawings, in which:

FIG. 1 is a plan view of a justifier accessory according to the present invention;

FIG. 2 is a front elevation view of the justifier of FIG. 1, wherein the front cover has been removed and the position of a slider modified.

FIG. 3 is a side view from the left of this justifier when locked in non-working position.

FIGS. 4, 5 and 6 are cross-sectional views of the justifier on lines IV-IV, V-V and VI-VI of FIG. 2, respectively, with certain parts not shown;

FIGS. 7 and 8 schematically show modified forms of escapement.

In the case of a justifier designated as an accessory (FIGS. 1 to 6), the mechanism is preferably housed in a casing consisting of a base 4, a left hand flange 5, a right hand flange 6 and a back plate 7 which may be used for securing the device to the typewriter by means of a bracket 8. Washers or a strip of resilient material (not shown) may be placed between the back plate 7 and the bracket 8. The outline of the typewriter cover is shown at 1, the 2-unit space bar at 2 and the 3-unit space bar at 3. In the front, the device is closed by a cover 9 which also partially covers the upper part thereof.

A rack 10 is positioned between flanges 5 and 6, and longitudinally maintained therebetween by pins 16 and 17. In the form shown, this rack comprises fourteen teeth each with substantially triangular profile, such as 11 and 12 near the right hand end of the rack and 13 and 14 near the left hand end—these teeth serve for escapement—and a locking tooth 15, the profile of which is here rectangular. A design with fourteen teeth makes it possible to actuate thirteen times at the most the space bar 3 before passing to space bar 2; its justification capacity is therefore thirteen units. The number of teeth

of the rack 10 may be increased to increase the justification capacity.

A rigid frame is made up of two parallel rods 20 and 21 to which two end blocks 30 and 50 are secured. The left hand block 30 is keyed on rod 20 by a pin 31 and on rod 21 by another pin 32 serving also to hook a spring. The right hand block 50 is keyed on the rods by pins such as 51. The rod 20, the ends of which pivot in the flanges 5 and 6, forms the swinging shaft of the frame. The ends of rod 21 are in contact with the inner walls of the flanges and therefore prevent the frame from longitudinally moving therebetween.

The master space bar 40 is secured to the upper faces of blocks 30 and 50: on the block 30, by a cap screw 42 and on the block 50 by a countersunk screw 43. When the operator presses on the portion 41 of the bar used as a key, the frame swings about the axis of its rod 20. If the operator finds it easier, the swinging of the frame may be also controlled by means of a key 44 partially covering one of the typewriter space bars—the 2-unit space bar in the present case. The key 44 is fixed on the block 50, upon the master space bar 40, by milled knobs 45 and it is removable.

It is relevant to note that keys 41 and 44 do not prohibit the direct actuation of the space bars 2 and 3, in the cases in which justification cannot be carried out automatically, or for any other reason.

The master space bar finally comprises slot 46 for head 76 of a slider 70 moving on rods 20 and 21 of the frame, and a setting scale (series of vertical figures 1 to 13, FIG. 1).

A plate 33 (FIG. 4) is secured to the left hand block 30 by a screw 34. A spring 35, hooked on the one hand onto the plate and, on the other hand, onto pin 36 of the left hand flange, constantly urges the left hand block toward a cam 37. This cam makes it possible to modify the rest position of the frame and therefore permits adjustment of the escapement.

The right hand block 50 (FIG. 6) carries a grooved wheel 52 with a drum 55 which freely turns about a shaft 56. The return cable 61 (FIG. 2) is hooked onto the pin 73 of the slider 70. This cable passes through the groove of the wheel 52 and slot 53 of said wheel; a washer 54 forms a flange in respect to the rounded portion joining the groove to the slot. The cable leaves the slot tangentially to the drum 55 around which it is wound before hooking onto the drawback spring 60. This spring is hooked on pin 32 of the left hand block, already mentioned.

The diameter of wheel 52 is much greater than that of the drum 55, in order that travel of the slider 70 under the action of the drawback spring 60 causes a comparatively small change in the spring length. Thus, the return force applied to the slider varies little throughout the range of operation. A sufficiently constant return force could be also obtained by substituting a drum housed spiral coiled spring with many turns for the wheel-drum arrangement.

The slider 70 carries (FIG. 5) the pin 73 for hooking the cable 61, the space bar control finger 74 fixed by two screws 75, and the head 76 moving in the slot 46. This head carries two parallel escapement teeth or dogs, freely sliding in the slider 70 and cooperating with the teeth of rack 10. A screw 77 housed in the head makes it possible to adjust the engagement depth of dogs 71, 72 in the rack toothings.

If i (FIG. 2) denotes the pitch of rack 10, the dog 72 is arranged at a distance of $1.5i$ to the left of dog 71. It follows that when the dog 71 rests on a tooth of the rack 10, the dog 72 is in line with the middle of the preceding space between two rack teeth. Besides, the dog 72 is situated behind dog 71 in plan view, in order to be normally outside the rack toothings, and little distance from it.

In FIG. 2, the slider 70 is set for justifying a line short by thirteen units. To this end, the dog 71 has been brought into contact with the tooth 13 of rack 10. When the operator presses upon the master space bar 40 (key 41 or key 44, depending upon whichever key he feels most convenient for use), the frame swings about the axis of its rod 20, the spring 35 is stretched and the dog 71 disengages itself laterally (in FIG. 5) from the tooth 13 of the rack. At the same time dog 72 enters into the rack toothing, at 0.5*i* to the left of tooth 14. During this movement, the space bar finger control 74 lowers the space bar 3 above which it is situated and the first 3-unit space of the line is introduced. When the dog 71 is completely disengaged from the tooth 13 of the rack, the slider 70 moves suddenly by 0.5*i* and dog 72 comes into contact with the tooth 14 of the rack. The dog 71 is then in line with the middle of the space between the tooth 13 of the rack and the rack tooth next to the right. When the operator releases the master space bar, the dog 72 progressively leaves the tooth 14 of the rack and, at the time the disengagement occurs, the dog 71 is stopped in turn by the rack toothing after the slider has travelled an additional distance of 0.5*i*. Thus the slider advances by one rack tooth at each action on the master space bar 40.

In FIG. 1, the slider 70 is in the position it has reached after the first twelve 3-unit spaces of the line under consideration have been introduced (or else, in the position which would correspond to the justification of a line short by one unit). Dog 71 rests against the tooth 11 of the rack and dog 72 is at 0.5*i* to the left of tooth 12 of the rack. When the master space bar 40 is lowered, the spring 35 is stretched, the dog 71 is laterally moved away (laterally in a cross-section view) from the rack tooth 11; and the dog 72, which has simultaneously penetrated into the rack toothing, comes to stop against the rack tooth 12 while the slider moves forward by 0.5*i*. During this lapse of time, the space bar control finger 74 has lowered the space bar 3 and the last 3-unit space of the line has been introduced. When the operator releases the master space bar 40, the spring 35 returns the frame to its rest position, the dog 72 slides along the tooth 12 of the rack to leave it laterally, and the dog 71 comes back into the rack plane. However, there will no longer be any rack tooth to stop it when dog 72 finally clears the rack tooth 12. At the time the escapement occurs, the slider 70 advances suddenly until coming to rest against the right hand block 50. The space bar control finger 74 is then above the 2-unit space bar, and all the spaces introduced by further actions on the master space bar will henceforth uniformly be 2-unit spaces. When the frame swings, the dogs 71 and 72 move inoperatively in free space.

The device is set by raising the head 76 so that the dog 71 clears the tops of the teeth of rack 10, moving the slider 70 toward the left up to a position slightly to the left of the setting figure required (figure 7, for instance, for a line short by seven units and marked "7" on the preparatory copy), laying the head back on the slider, thus engaging the dog 71 in a suitable space in the rack toothing, and finally releasing the slider. The traction of the return cable 61 immediately brings the dog 71 into contact with the required rack tooth.

When the justifier is not being used, access to the space bars may be made completely free. To do so, the key 44 may be either removed or set back on the block 50 by means of the holes 47 and milled knobs 45. Next, the operator slightly raises the head 76 and pulls the slider 70 until it stops against the block 30. In these conditions, the dog 72 comes to a position slightly to the left of the locking tooth 15 of the rack. The operator replaces the head on the slider, presses on the master space bar 40 and releases the slider permitting the dog 72 to come to rest against the locking tooth 15. While keeping the master space bar lowered, the operator puts the bolt in locking position. This bolt, denoted by 80 as a whole, con-

sists of a bent round rod 81, the nib 82 of which holds the upper face of the master space bar and includes a catch 84. The bolt shaft slides in the left hand flange 5 and is returned by a spring 83. In the non-working position, the space bar control finger 74 is to the left of the space bar 3 and lower than it; in the same way, the key 41 of the master space bar is lower than the space bar 3.

The arrangement described above is likely to be modified, as one skilled in the art can easily conceive. The 10 housing of the justifier within a casing, its system of attachment to the typewriter, the structure of the swinging part, the type of escapement, the slider return system, the locking arrangement of the justifier, the position of the master space bar or keys thereof with respect to the 15 usual space bars, etc., may vary. It is possible, for instance, to arrange the keys of the master space bar so that they are lateral to the space bars and level therewith, or to provide one key only, etc.

Among these modifications, a large number may concern 20 the type of escapement provided. The mechanism embodied to the form described as an example is of the two-dog type, the dogs engaging alternately the toothing of a single rack. It is clear that one may use as well a single dog (FIG. 7) cooperating with two identical racks 25 101, 102, the teeth of which are longitudinally set off with respect to each other by half a rack pitch; or using two dogs 71, 72, with each cooperating with its own rack 101, 102 (FIG. 8). Also, the escapement release 30 may be from translation instead of a swinging type. The 35 escapement gear may also be of the type embodying a wheel, such as is commonly used on typewriters, and its dog or dogs may consist of pawls, or the like.

The putting of the dogs out of engagement with the 35 rack teeth is necessary for the initial setting of the slider as well as resetting when the required setting has been accidentally overrun. It is in fact impossible, in this case, to come back to the correct position by a few actions on the master space bar. In the escapement arrangement 40 described, the rack is fixed in position and the disengaging of the dogs therefrom is effected by lifting said dogs. But the dogs may remain at a fixed level and the rack or racks be made clearable in respect to them by a swinging motion about a longitudinal axis, by a fore to aft translation or a vertical translation etc. To sum up, all kinds 45 of escapement arrangements and clearing designs for the escapement may be used, giving as much modified forms of the invention.

When the justifying device, instead of constituting an 50 accessory of the kind set forth hereinbefore, is embodied to the typewriter at the time of its building up in order to form a part thereof the same as any other structural assembly, it is housed under the cover and only the members which the operator should handle protrude: (a) a 55 master key or bar for introducing the spaces in the course of justification, this master key or bar being integral with the member of the embodied justifying device corresponding to the master space bar 40 of the accessory version; (b) a justification setting knob, corresponding to the head 76—or replacing part—of the accessory version; and 60 eventually (c) a justifier locking control corresponding to the lock 80, or similar part, of the accessory version.

The space bar control finger 74, when placed also under the typewriter cover, no longer controls the space bars from above, but rather at their base, through a 65 longitudinal strip, flange or rib with which each space bar is provided. Alternatively, it controls directly the pairs of levers each carrying a space bar, through longitudinal plates secured to each of these pairs of levers.

I claim:

70 1. A justifying device for typewriters having at least two space bars for typing spaces of two different widths, comprising:

a space bar control finger for actuating the space bars; a slider carrying said space bar control finger through a longitudinal movement;

a frame carrying the slider, said frame being capable of swing about a horizontal axis;
 a master space bar rigidly mounted on said frame and adapted to depress said space bars through the medium of the slider and space bar control finger;
 a return system for said slider and space bar control finger;
 an escapement allowing the slider and space bar control finger to move stepwise each time said master space bar is manually actuated, and
 means for setting the initial position of the slider and space bar control finger whereby said finger is in actuating position with respect to one of said space bars until a predetermined number of actuations has been effected on the master space bar, after which the slider and space bar control finger move into actuating position with respect to another one of the space bars.

2. A justifying device as provided for in claim 1, wherein in said escapement comprises a fixed rack and two dogs 20 co-operating therewith, one of said dogs being disengageable from said rack by a raising movement to allow for the stepwise movement of the slider and space bar control finger.

3. A justifying device according to claim 1, wherein said escapement comprises two fixed racks and two dogs each co-operating with one of said racks, both dogs being disengageable from their rack by a raising movement to allow for the stepwise movement of the slider and space bar control finger. 25

4. A justifying device according to claim 1, wherein said escapement comprises two fixed racks and a single

dog co-operating therewith, said dog being disengageable from said racks by a raising movement to allow for the stepwise movement of the slider and space bar control finger.

5. A justifying device according to claim 1, wherein the slider and space bar control finger return system is of the geared-down type consisting of a wheel with a drum of smaller diameter, a return cable being attached to the slider and passing first on the wheel and then around the drum and a return spring to which the return cable is attached.

6. A justifying device according to claim 1, wherein the master space bar is provided with a removable key extending over that of one of the space bars most frequently used in conventional typing.

7. A justifying device according to claim 1, wherein the master space bar is provided with a key extending over one of the space bars and a cam member by which the rest position of the frame is adjustable.

8. A justifying device according to claim 1, such device being enclosed in a casing provided with means by which it is attached to the typewriter, said means including a bracket secured to the typewriter frame and to which the casing is detachably attached without any connection to a movable part of the typewriter.
